DESIGN FOR A LIGHTING DEVICE

Jerome Nathan, New York, N. Y., and James C. Haberman, Springfield, Mass.

Application April 5, 1947, Serial No. 138,170

Term of patent 3½ years

(Cl. D48—27)

To all whom it may concern:

Be it known that we, Jerome Nathan and James C. Haberman, citizens of the United States and residents respectively of the County of Queens, city and State of New York, and the county of Hampden, city of Springfield, State of Massachusetts, have invented a new, original, and ornamental Design for a Lighting Device, of which the following is a specification, reference being had to the accompanying drawing, forming part thereof, in which:

Fig. 1 is a top plan view of a lighting device, embodying our new design.

Fig. 2 is a front end elevation of the same device.

Fig. 3 is a side elevation of the same device and

Fig. 4 is a rear end elevation of the same device.

We claim:

The ornamental design for a lighting device, as shown.

JEROME NATHAN.
JAMES C. HABERMAN.
